UNITED STATES PATENT OFFICE

150,296

DESIGN FOR A LAWN SPRINKLER

Francis C. Hubbard, Minneapolis, Minn.

Application March 11, 1946, Serial No. 127,355

Term of patent 7 years

(Cl. D91—1)

To all whom it may concern:

Be it known that I, Francis C. Hubbard, a citizen of the United States, residing at Minneapolis, in the county of Hennepin and State of Minnesota, have invented a new, original, and ornamental Design for Lawn Sprinkler, of which the following is a specification, reference being had to the accompanying drawing, forming part thereof.

Fig. 1 is a perspective view of a lawn sprinkler showing my new design; and

Fig. 2 is a side elevational view thereof.

The dominant features of the design reside in the portions shown in full lines.

I claim:

The ornamental design for a lawn sprinkler, as shown and described.

FRANCIS C. HUBBARD.
